BIRDHOUSE

Albert D. Hocker, 1418 W. Franklin St.,
Evansville, Ind. 47710

Filed Apr. 26, 1968, Ser. No. 11,642

Term of patent 14 years

Int. Cl. D30—01

U.S. Cl. D30—3

FIG. 3

FIG. 4

FIG. 1 is a view in front elevation of a birdhouse, showing my new design, the rear elevation being a mirror image thereof;

FIG. 2 is a view in side elevation of the claimed design, where the opposite side is a mirror image thereof;

FIG. 3 is a top plan view of the claimed design; and

FIG. 4 is a bottom plan view of the claimed design.

The essential features of the design reside in the full line portions.

I claim:

The ornamental design for a birdhouse, as shown and described.
